CLAIM

The ornamental design for glasses, as shown and described.

DESCRIPTION

FIG. 1 is a front elevational view of glasses showing the new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a first perspective view thereof;

FIG. 8 is a second perspective view thereof;

FIG. 9 is an enlarged view of the encircled portion '9' in FIG. 1;

FIG. 10 is an enlarged view of the encircled portion '10' in FIG. 2;

FIG. 11 is an enlarged view of the encircled portion '11' in FIG. 3;

FIG. 12 is an enlarged view of the encircled portion '12' in FIG. 6;

FIG. 13 is an enlarged view of the encircled portion '13' in FIG. 7; and,

FIG. 14 is an enlarged view of the encircled portion '14' in FIG. 8.

The broken lines shown in the drawings illustrate portions of the article and form no part of the claimed design. The larger scale broken lines demarcate the enlarged views and form no part of the claimed design.

1 Claim, 14 Drawing Sheets
